UNITED STATES PATENT OFFICE.

MAURICE ALLAND, OF ATLANTIC CITY, NEW JERSEY.

MAGAZINE PENCIL.

Application filed December 6, 1923. Serial No. 678,854.

To all whom it may concern:

Be it known that I, MAURICE ALLAND, a citizen of the United States, residing at Atlantic City, in the county of Atlantic and State of New Jersey, have invented certain new and useful Improvements in Magazine Pencils, of which the following is a specification.

The object of this invention is to provide 10 an improved pencil of the magazine type, wherein a store of the so-called "leads" is maintained for renewing the writing point, or that portion of a lead exposed for the purpose of writing.

15 Another object is to provide in such a pencil means, connected with the piece of lead being used, which is adapted to cooperate with other means within the pencil casing, whereby the extent to which the lead 20 projects from said casing is automatically governed in accordance with predetermined details hereinafter set forth.

A further object is to provide such a 25 pencil with an elongated cylindrical eraser, means for operatively supporting said eraser, and means for actuating said supporting means, whereby when the exposed portion of the eraser is worn away the supporting means permits the cylindriform member to be withdrawn further, and then 30 clamped so as to prevent its accidental retreat into the pencil casing.

With these and other objects in view, the 35 present invention comprises additional novel details of construction and operation hereinafter fully brought out in the following description, when read in conjunction with the accompanying drawings, in which Fig. 1 is a longitudinal diametrical section of one embodiment of the present invention; Fig. 2 is an elevation of the same; Fig. 3 is a longitudinal section of the lower portion of the device showing the parts in different relative positions than that exhibited, 45 in Fig. 1; Fig. 4 is a transverse section on the line 4—4 of Fig. 2; Figs. 5 and 6 are transverse sections of the device as shown in Fig. 2, but at the respective points as indicated by the lines 5—5 and 6—6 on Fig. 50 1; Fig. 7 is a fragmentary elevation of the upper eraser-supporting portion of the device, with the clamping member removed; Fig. 8 is a fragmentary elevation of the lead-supporting portion with the clamping

member removed; and Fig. 9 is an elevation 55 of the lead clamping member per se.

Referring to the drawings, a cylindrical casing 1 is provided, comprising a magazine for holding spare leads, said casing being preferably enlarged at 1 and 2 and provided 60 with a reduced end portion 3, which is provided with a bore 4 comprising a continuation of the magazine chamber within the casing proper. Said end portion 3 is longitudinally cut at spaced regions 5 to provide 65 intervening radially resilient fingers 6.

Said reduced portion is externally threaded adjacent to the enlarged portion 2 and is adapted to receive the internally threaded portion 7 of a clamping member 70 8, which is preferably knurled circumferentially at 9, and the inner surface of the walls of which preferably taper, so that upon screwing said clamp into the position shown in Figs. 1 and 2, the fingers 6 are flexed 75 radially inwardly to grip and secure against longitudinal movement a cylindriform eraser 10.

So far as the invention is concerned, it 80 would be the equivalent of this construction to have the outer surfaces of the fingers 6 tapered, and the clamping member provided internally with a shoulder or other co-operating portion which would operate in a similar manner to contract said fingers 85 about the said eraser.

The opposite end portion of the casing 1 is internally threaded at 11, the inner end of which threading terminates adjacent to a plane shoulder 12. A second casing member 13 is provided with a reduced and externally threaded end portion 14, which engages the threads 11, and secures against the shoulder 12 the disc-like member 15, which is provided with a central bore 16 adapted 90 to receive from the magazine section 1 a lead 17.

Secured to the member 15 and in axial alignment therewith is a tube 18, which terminates at 19 quite near to the lower open end of an enlarged extension 20 of the second casing 13. The tube 18 is surrounded by a tube 21, which serves to stiffen the former, and is secured rigidly to, yet spaced a uniform distance from, the walls of the casing 13 by means of an annular partition 22. 100 105

This second tube extends beyond the

lower limits of the first tube, is slotted at 23 to provide radially yielding fingers 24, and is externally threaded at 25, while the free end portions of said fingers are tapered 5 at 26.

It will be obvious from this construction that when a lead 17 extends between the fingers 24, a hollow conical member 27, internally threaded at 28 and providing it 10 with tapering side walls 29, may be screwed upon the threads 25 of said fingers, with the result that the free end portions of the latter are radially compressed upon the outer surface of the latter.

15 It should also be noted, by reference to Figs. 1 and 3, that the lead being used is provided with an encircling sleeve 30, of light-weight metal and which should frictionally engage the lead. With this construction, and the device in the arrangement shown in Fig. 1, it is assumed that the exposed point of the lead is worn away to the extent shown in Fig. 2, and that it is desired to expose an additional amount of 25 lead.

The clamping member 27 is separated entirely from the lead-supporting fingers and is represented by the relationship between 30 Figs. 8 and 9. An additional quarter-inch or thereabouts of the blunt lead will be exposed, and which may be manually gripped by the fingers and pulled longitudinally outwardly as far as desired, as for instance to the extent of one-half to a three-quarters-inch.

During this action, the sleeve 30 impinges against radially aligned shoulders 31 provided upon the interior of the free end 40 portions of the contractable fingers 24. The clamping member 27 is thereupon screwed, as shown in Fig. 3, upon said fingers, that is, until it is slightly spaced from the casing member 13, of which it normally forms a continuation.

45 The pencil with the protruding lead is then pressed gently upon any available surface 32 until the lead is forced upwardly into the casing, the sleeve 30 then impinging upon the free end portion 19 of the tube 50 18, and sliding up the lead until the latter comes to rest.

Upon raising the pencil for co-operation with the said surface 32, and with the clamping member still loose, the lead is free 55 to drop until the sleeve 30 rests upon the shoulders 31. Said clamping member then being rotated into the position shown in Figs. 1 and 2, the fingers 24 grip the lead and restrain it against its receding into the 60 said casing.

Obviously, this operation can be repeated as many times as necessary, until a given bar of lead is completely used, that is, has wasted away in writing. Thereupon the 65 clamping member 8 is removed entirely

from the fingers 6 or at least until it is possible to remove the eraser 10, whereupon another of the leads 17 in the magazine may be extracted, the eraser and its clamping member replaced and the new lead slid into the 70 fingers 24 and through the sleeve 30, whereupon the proper adjustment for writing purposes is thereby attained as hereinbefore described.

Having thus described my invention, what 75 I claim and desire to protect by Letters Patent of the United States is:—

1. In a pencil, the combination of a casing having an outlet, a removable channelled magazine member within said casing 80 providing a shoulder in the neighborhood of said outlet, a plurality of radially yielding fingers comprising a unitary part of said casing and adapted to surround a lead extending from said member and through said 85 outlet, said fingers jointly having an enlarged bore terminating in a circumferential shoulder in one direction, a sleeve frictionally carried by a lead and movable within said bore between the limits set by said 90 shoulders, to automatically predetermine the extent that the lead shall extend from said casing, an auxiliary member having an aperture through which the lead projects and provided with inner converging walls, and 95 threaded means to removably secure said last-named member upon and as a continuation of said casing, said fingers being contracted upon and operative to normally prevent the inward movement of the lead as 100 said last-named member is screwed upon said casing.

2. In a pencil, the combination of a casing closed at one end by a removable partition having an aperture, a second hollow casing 105 removably secured to and operative to serve as a continuation of said first casing and forming a lead magazine, a tubular member extending from said partition through said first casing towards its opposite end and terminating in a shoulder, a second tubular member connected with said first casing and surrounding said first tubular member and at its free end being longitudinally slotted to provide radially yielding fingers 110 providing an inwardly directed shoulder and frictionally engaging a lead extending therethrough from within said first tubular member, and a sleeve adapted to surround a lead in frictional engagement therewith and having a longitudinal movement limited by said shoulders.

3. In a pencil, the combination of a casing closed at one end by a removable partition having an aperture, a second hollow casing 125 removably secured to and operative to serve as a continuation of said first casing and forming a lead magazine, a tubular member extending from said partition through said first casing towards its opposite end and 130

terminating in a shoulder, a second tubular member connected with said first casing and surrounding said first tubular member and at its free end being longitudinally slotted 5 to provide radially yielding fingers providing an inwardly directed shoulder and frictionally engaging a lead extending therethrough from within said first tubular member, a sleeve adapted to surround a lead in frictional engagement therewith and having a longitudinal movement limited by said shoulder, a hollow member having a longitudinal movement limited by said shoulders, and a hollow member having tapering inner walls and a central aperture through which a lead protrudes, said last-named member being adapted to be screwed upon said fingers and form a continuation of said first casing, to contract said fingers and thereby prevent an accidental inward movement of said lead.

20 4. In a pencil, the combination of a casing closed at one end by a removable partition having an aperture, a second hollow casing removably secured to and operative to serve as a continuation of said first casing and forming a lead magazine, a tubular member extending from said partition through said first casing towards its opposite end and terminating in a shoulder, a second tubular member connected with said

first casing and surrounding said first tubular member and at its free end being longitudinally slotted to provide radially yielding fingers providing an inwardly directed shoulder and frictionally engaging a lead extending therethrough from within said first tubular member, a sleeve adapted to surround a lead in frictional engagement therewith and having a longitudinal movement limited by said shoulder, a hollow member having tapering inner walls and a central aperture through which a lead protrudes, said last-named member being adapted to be screwed upon said fingers and form a continuation of said first casing, to contract said fingers and thereby prevent an accidental inward movement of said lead, 35 said partition and first tubular member being integrally connected and removable from said first casing, the opposite end of said second casing being slotted to provide radially yielding fingers adapted to receive an eraser member, and means adapted to be screwed upon said last-named fingers to contract them upon and prevent longitudinal movement of an eraser positioned therein. 45

50 In testimony whereof I have affixed my signature.

MAURICE ALLAND.
